(57) **CLAIM**

The ornamental design for a camera lens cover, as shown and described.

DESCRIPTION

FIG. 1 is a top, right and front perspective view of a camera lens cover showing my new design, shown in a first position;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top, right and front perspective view thereof, shown in a second position.

The phantom lines shown in the figures are shown for illustrative purposes only and form no part of the design.
